UNITED STATES PATENT OFFICE.

JOHN CUTHBERT, OF CHICAGO, ILLINOIS, ASSIGNOR TO ECONOMY FUSE AND MANUFACTURING COMPANY, OF CHICAGO, ILLINOIS, A CORPORATION OF NEW YORK.

ELECTRIC FIXTURE.

Application filed May 21, 1920. Serial No. 383,083.

To all whom it may concern:

Be it known that I, JOHN CUTHBERT, a citizen of the United States, residing at Chicago, in the county of Cook and State of Illinois, have invented certain new and useful Improvements in Electric Fixtures, of which the following is a specification.

This invention relates to electric fixtures.

More particularly it relates to fixtures including electric sockets to which may be attached electric lamps, plug connectors, etc.

It is sometimes necessary to provide electric fixtures wherein lamp sockets and the like are secured to or incorporated with pipe fittings, bracket-plates, canopies, shades, reflectors, etc. It has been the usual practice to secure the sockets to the pipes, canopies, shades, reflectors and the like, by means of set screws, screw or ring clamps, etc. The canopies, shades, reflectors, etc., sometimes have been threaded to receive a threaded projection on the socket. Such expedients often prove unsatisfactory. Set screws are not always permanent and reliable. Where the socket and canopy, shade, reflector, or the like, are complementarily threaded, it may be necessary to rotate the socket in order to secure it in place. This is objectionable as the conductors, when fastened to the socket terminals, are twisted and may be broken or loosened from the terminals.

An object of the present invention is to provide an improved electric fixture.

Another object is to provide for the ready and easy securing of electric sockets to pipe fittings, canopies, shades, reflectors, etc.

Another object is to provide a simple and inexpensive fastener for an electric socket.

Other objects and advantages will appear from the specification and claims.

Embodiments of the invention are shown in the accompanying drawing.

In the drawing:—

Fig. 1 is a perspective of a socket and canopy.

Fig. 2 is a longitudinal section of the structure shown in Fig. 1.

Fig. 3 is a perspective of a socket combined with a canopy and pipe fitting.

Fig. 4 is a longitudinal section of the structure shown in Fig. 3, and

Fig. 5, is a perspective of a clamping sleeve.

Figs. 1 and 2 will first be described.

The fixture shown comprises an electric 55 socket 10 and a support in the form of a canopy 11. The socket may be of any desired form and of either the key or keyless type. Examples of sockets which may be satisfactorily used are illustrated in my co-pending application Serial No. 383,082, filed May 21, 1920, and application Serial No. 383,085, filed May 21, 1920. It has an exteriorly threaded projection 12 provided with an axial opening thru which conductors may 60 65 pass into the interior of the socket.

Canopy 11 is represented as of inverted bell shape. It may be adapted, in any desired manner, to be held against a wall or other support. The canopy has an opening 70 through its center for the reception of socket projection 12. This opening need not be threaded.

An interiorly threaded nipple 13 is provided to clamp the socket and canopy into a 75 unitary structure. Nipple 13 has an opening therethrough for the passage of conductors and its threads are adapted to register with the threads on socket projection 12.

To assemble the structure, projection 12 of 80 the socket is inserted through the opening of the canopy. Then nipple 13 is screwed down upon the projection, binding the edges of the canopy opening between the lower edge of the nipple and the rear shoulder of the 85 socket.

The conductors may first be connected to the socket terminals. There is no necessity for thereafter twisting the conductors as the socket is inserted in the canopy by a straight 90 axial movement, and the clamping of the parts together, by the tightening of the nipple against the rear of the canopy, does not twist the conductors.

The socket may be placed on the concave 95 side of the support and the nipple clamped down against the convex side thereof. This arrangement would be used where the support is a shade, reflector or rosette. The action of the elements are precisely the same 100 as that previously described.

Figs. 3 and 4 show a socket and a support in the form of a canopy, clamped to a pipe fitting to comprise, in effect, a unitary structure.

Socket 15, as before, has at its rear, an

exteriorly threaded projection 16, through which the conductors pass into the interior. Support 17 in the form of a canopy has an opening therein for receiving socket projection 16. The center of canopy 17, about its opening, is formed into a small rosette or nest for fitting the rear of the socket. 5
Socket 15 and canopy 17 are fitted and secured to the end of a pipe 18 through 10 which the conductors are led to the socket. A small flexible sleeve 19 is fitted over the end of pipe 18. Sleeve 19 is composed of suitable material such as soft spring steel. It may be slotted as shown to make it more 15 flexible. Each end of sleeve 19 is chambered to provide wedging surfaces 20. An interiorly threaded nipple 21, similar to that previously described, is adapted to be threaded upon socket projection 16 and clamp 20 the socket, canopy and pipe 18 together. The bore of nipple 21 is tapered, the smaller end being toward the rear as clearly shown in Fig. 4. As nipple 21 is threaded upon projection 16, the tapered 25 inner wall of the nipple bore engages the rear wedging surface 20 of sleeve 19. The sleeve is forced forward toward the socket so that its forward wedging surface 20 engages the upper edge of projection 16. 30 The sleeve is also compressed to tightly clamp pipe 18. When the nipple is threaded so that it clamps the canopy tightly against the rear of the socket, sleeve 16, because of the wedging action of its forward 35 and rear wedging surfaces against the edge of projection 16 and the interior wall of nipple 21, respectively, tightly grips the pipe. The socket, canopy and pipe are thus firmly clamped together. 40 The parts may be readily separated by loosening and removing the nipple. Since the parts are assembled by merely uniting them by straight axial movement, there is no necessity for turning the socket and the 45 pipe and the conductors are saved from twisting.

The supports may take various forms and be used for various purposes. The word "support" is to be taken to mean base- 50 plate, canopy, shade, reflector and similar fittings adapted for use with electric sockets.

Having described my invention what I

claim as new and desire to secure by Letters Patent is:—

55

1. An electric fixture comprising an electric socket having an open threaded projection through which conductors pass to the interior of the socket, a socket support having an opening therein and through 60 which said projection extends, a pipe gripping sleeve within the opening in said projection, and a nipple fitting said projection and cooperating with said support and said sleeve to clamp said socket to said support 65 and a pipe.

2. An electric fixture having a socket support with an opening therethrough, an electric socket having a threaded projection with an opening therethrough for receiving the end of a pipe fitting and conductors, a compressible flexible sleeve within the opening in said projection and for surrounding a pipe fitting, and a nipple fitting said projection and for clamping said socket to said 70 support and compressing said sleeve upon a pipe fitting to hold said socket, support and a pipe fitting together.

3. An electric fixture comprising an electric socket having an externally threaded projection with an opening therethrough for receiving the end of a pipe fitting and conductors, a compressible flexible sleeve within the opening in said projection and for surrounding a pipe fitting inserted in 80 said opening, a socket support having an opening therethrough for receiving said projection, and an internally threaded nipple to be screwed upon said projection and cooperating with said support and said 85 sleeve to clamp the support, sleeve and pipe fitting together.

4. An electric fixture comprising a socket having an exteriorly threaded projection, an interiorly threaded nipple for fitting 95 said projection and having a tapered bore, and a cylindrical flexible sleeve fitting within the bore of said nipple and having a wedging surface cooperating with the tapered bore thereof whereby said sleeve is 100 compressed and a socket support clamped between said socket and said nipple.

In testimony whereof I hereunto subscribe my name.

JOHN CUTHBERT.
